UNITED STATES PATENT OFFICE.

CARL A. SCHOEN, OF HOUMA, LOUISIANA.

MIXING VALVE.

Application filed September 22, 1922. Serial No. 589,846.

This invention relates to internal combustion engines, the general object of the invention being to provide means whereby the engine can be operated on gas fuel instead of liquid fuel with but little change to the engine parts.

Another object of the invention is to so arrange the parts of the invention that the engine can be run on liquid fuel whenever desired and without removing the gas feeding mechanism.

A further object of the invention is to provide a tank for holding natural gas with means for mixing the same with the air and introducing the mixture into the air intake of the carburetor of the engine.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a fragmentary sectional view showing the invention in use.

Figure 2 is a detail view showing the manner of connecting the mixing device with the air intake of the carburetor.

Figure 3 is a longitudinal sectional view of the mixing device.

Figure 4 is a similar view but showing the valve in open position.

Figure 5 is an end view of the mixing device.

Figure 6 is a section on line 6—6 of Figure 3.

Figure 7 is a sectional detail view of the valve.

In these views 1 indicates a mixing device which has one end inserted in the air intake 2 of the carburetor A of the engine. The device is held in place by the clips 3. The device is connected by the piping 4 with a tank 5 which is adapted to be filled with compressed natural gas and a pressure gage 6 is connected with the pipeline by the pipe 7, the gage being preferably arranged on the dash of the vehicle. A pressure regulating valve 8 is arranged in the pipeline for reducing the pressure of the gas passed into the mixer. The flow of gas into the mixer

is controlled by a valve 9 which is normally held upon its seat by the spring 10, the valve being opened by the suction created by the engine. This valve includes a hollow tubular stem which slides through a longitudinal bore constituting the inlet of the mixing device at one end thereof, and which stem 8' is provided with openings 9' at diametrically opposite points and immediately adjacent the valve proper, whereby the fuel is allowed to pass through said openings when the valve is moved far enough away from its seat to permit the openings to move beyond the bore. Air ports 11 are formed in the mixer and these ports are adjustable by means of the sleeve 12 arranged on the mixer and having the ports 13 therein.

When the engine is to be run by gas the needle valve of the carburetor is closed so as to shut off the supply of gasoline or other fuel and the valve in the tank is opened to permit the gas to flow through the pipeline, past the regulating valve 8 and into the mixing device. In this device the gas is mixed with air flowing through the ports 11 and the mixture then passes into the cylinders where it is exploded in the usual manner. As will be seen the valve 9 will prevent the flow of gas into the mixing device until the engine is in operation when the suction created by the moving pistons will act to open the valve 9 against the action of its spring and draw in a supply of gas and air to form an explosive mixture. The gage 6 will indicate the amount of gas in the tank and the parts are so arranged that the tank can be easily substituted by a full one when it becomes empty. Whenever desired the vehicle can be run on liquid fuel by opening the needle valve to permit the fuel to pass into the carburetor.

I have found that by the use of natural gas the operation of an internal combustion motor is more efficient than when using liquid fuel and there is no formation of carbon. The invention is easily and quickly applied to an internal combustion engine without making any changes thereto and the engine can be run on liquid fuel whenever desired by simply opening the needle valve. The engine is controlled in the usual manner by the throttle and accelerator. As the valve 9 is normally held closed by its spring the gas in the tank can be compressed to a considerable extent so that a large quantity of gas can be carried in the tank.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

- 10 A fuel and air mixing device comprising a hollow cylindrical body having an outlet opening at one end, and a centrally located longitudinal bore at the other end constituting the inlet, a nipple projecting from the last mentioned end of said body, a spring pressed sliding valve arranged within said

body, said valve including a hollow stem 20
slidable within the bore and guiding said valve in its movements, said stem having openings immediately adjacent the valve 25
through which the fluid escapes from said bore when the valve is moved away from its seat by pressure of the fluid, said body having a circumferential series of air inlet openings, and a sleeve rotatably mounted on the 25
body and having openings adapted to be brought into registration with the openings in said body to regulate the admission of air into the mixer.

In testimony whereof I affix my signature.

CARL A. SCHOEN.
